Ampex Corporation, Redwood City, Calif.

Filed Oct. 21, 1970, Ser. No. 25,591

Term of patent 14 years

Int. Cl. D14—02

U.S. Cl. D26—5

The sole figure is a front, top and right side perspective view of a magnetic tape transport, showing my new design, the bottom and rear being conventionally plain, and the left side being a mirror image of the right side.

I claim:

The ornamental design for a magnetic tape transport, substantially as shown and described.
